UNITED STATES PATENT OFFICE.

FREDERICK C. ZOBEL, OF NEW YORK, N. Y.

INTERLOCKING HINGE.

1,113,278.

Specification of Letters Patent.

Patented Oct. 13, 1914.

Application filed December 4, 1911. Serial No. 663,739.

To all whom it may concern:

Be it known that I, FREDERICK C. ZOBEL, a citizen of the United States of America, residing at New York city, State and county 5 of New York, have invented certain new and useful Improvements in Interlocking Hinges, of which the following is a specification.

My invention relates to door hinges and 10 comprises an improved form of interlocking hinge which prevents the removal from the doorway of a closed door even if the hinge pintle is removed.

Recent instances of great loss of life resulting in cases of fire from the use of doors 15 opening inwardly have caused a demand for the employment of outwardly opening doors. In such cases, the pintle of the hinges being 20 on the outside, it is easy for unauthorized persons to remove the pintles, open the door and so obtain access to the room or building. I have invented an interlocking form of hinge which holds the two leaves of the hinge together even after the pintle has been 25 removed, and so avoids the above mentioned difficulty.

The best form of apparatus at present known to me embodying my invention is 30 illustrated in the accompanying sheet of drawing in which—

Figure 1 is a view of the hinge with the leaves opened. Fig. 2 is a cross section of the hinge closed, taken on lines 2—2 of Fig. 1. Fig. 3 is a cross section on line 3—3 of Fig. 1. Fig. 4 shows a modification and Fig. 5 is a cross section on lines 5—5 of Fig. 4.

Throughout the drawings like reference characters indicate like parts. 40 1 and 2 are the leaves of an ordinary door hinge pivoted together by pintle 3. The usual countersunk screw holes for use in fastening one hinge leaf to the door and the other leaf to the jamb are indicated at 45 9, 9. The leaves of such hinges at the present time are often made by stamping them out of strips of metal. In such operation it is a simple matter to also stamp up tongues 4, 4, out of one leaf, and to cut out 50 openings, 5, 5 from the other leaf with which the tongues 4, 4 may engage when the

door is closed. Such engagement is shown in Figs. 2 and 3.

The tongues 4, 4, are preferably cut so that their edges 7 and 8 are curved to arcs whose 55 common center is the axis of the pintle 3. This does not interfere with the engagement and disengagement of the two leaves when the hinge is opened or shut by the rotation of one leaf with reference to the other on 60 the pintle of the hinge, but it produces a hooked projection which further interferes with any attempt to remove the door by taking out the hinge pintle, and prevents the separation of the leaves by wedges or 65 other instruments designed to disengage the projections in that way.

In the construction shown in Figs. 4 and 5, each leaf has one or more stamped up tongues 5, 5, formed on it, each tongue engaging the slot 6, formed by stamping up 70 the opposite tongue in the other leaf. This produces greater security by the double engagement, and also renders it possible to employ one and the same die in stamping 75 both leaves; the two leaves being duplicates turned end for end before assembling them for the hinge.

The advantages of my invention comprise its cheapness, and the security afforded 80 thereby. The projections being integral with the hinge leaves cannot be loosened therefrom.

Having described my invention, I claim—

1. A door hinge having projections formed 85 integral with one leaf and openings adapted to receive said projections formed in the other leaf, said projections being hook-shaped.

2. A door hinge composed of two leaves 90 each of which is a duplicate of the other, and has an inwardly projecting tongue formed by stamping out and bending inwardly a portion of the hinge butt, whereby, when the hinge is closed the tongue on each 95 leaf will enter the recess formed by stamping up the tongue on the other leaf.

FREDERICK C. ZOBEL.
